UNITED STATES PATENT OFFICE.

JAMES W. MCLEAN, OF INDIANAPOLIS, INDIANA.

IMPROVED GATE-LATCH.

Specification forming part of Letters Patent No. 55,326, dated June 5, 1866.

To all whom it may concern:

Be it known that I, JAMES W. MCLEAN, of Indianapolis, in the county of Marion and State of Indiana, have invented certain new and useful Improvements in the Construction and Arrangement of Gate-Latches; and I do hereby declare that the following is a full, clear, and exact description of the same, reference being had to the accompanying drawings and the letters marked thereon.

Figure 1 shows the latch in its position upon the gate, having the handles withdrawn from the same. Fig. 2 shows the catch-piece or latch. Fig. 3 shows the cover or top of the case. Fig. 4 shows the under part of the case. Fig. 5 shows the edge of the latch with the handles in place.

A is the latch; B, the top, and C the bottom or under part, of the case or latch-frame.

D is an inclined projection upon the upper arm of the latch A, and is operated upon by the pin G for the purpose of raising the latch, and serves as a stop or catch in holding the gate closed.

E is an inclined projection upon the lower arm of the latch A, and is designed to bring the latch down over the pin G, so that the catch-projection D covers the same when the gate is shut.

H is the handle by which the latch is operated in opening the gate.

The following is the operation of the latch: The latch, being operated by the handle H, turns upon its axis, being held by the cases B and C, between which it operates, raising the catch-projection B off from over the pin G, allowing the gate to swing open. In shutting the gate, as the same is swung together the catch-projection D strikes the catch-pin G and is thrown up until the pin G is passed by the same, and, striking the projection E, throws the same down, bringing the catch-projection D down over the catch-pin G, thus holding the gate firmly. The closing of the gate or the fastening of the same is secured by constructing the projection E so that the rebound caused by the concussion of the pin G will be in a vertical direction, the required angle being about forty-five degrees, as is well understood.

What I claim as my invention, and desire to secure by Letters Patent, is—

The latch A, with projections D and E, when constructed and operated substantially as and for the purposes set forth.

JAMES W. MCLEAN.
